CLAIM

The ornamental design for an electronic camera, as shown and described.

DESCRIPTION

FIG. 1 is a top, front and side perspective view of an electronic camera showing our new design;

FIG. 2 is a front elevational view thereof;

FIG. 3 is a top plan view thereof;

FIG. 4 is a bottom plan view thereof;

FIG. 5 is a side elevational view thereof from the left of FIG. 2;

FIG. 6 is a side elevational view thereof from the right of FIG. 2; and,

FIG. 7 is a view similar to FIG. 1, but with the parts in a different position.

The broken lines show environmental structure and do not form a part of the design claimed in the present application.
